UNITED STATES PATENT OFFICE.

JOHN B. BARTHOLOMEW, OF PEORIA, ILLINOIS, ASSIGNOR TO AVERY COMPANY, A CORPORATION OF ILLINOIS.

WAGON.

1,073,837.

Specification of Letters Patent. Patented Sept. 23, 1913.

Original application filed March 31, 1910, Serial No. 552,685. Divided and this application filed May 19, 1910. Serial No. 562,204.

To all whom it may concern:

Be it known that I, JOHN B. BARTHOLOMEW, a citizen of the United States, residing at Peoria, in the county of Peoria and State of Illinois, have invented certain new and useful Improvements in Wagons, of which the following is a specification, reference being had therein to the accompanying drawing.

10 This invention relates to wagons, and especially to wagons of that type which are adapted to be drawn by traction engines, either singly or in trains.

15 A wagon embodying my invention is adapted for carrying crushed rock or other similar heavy materials.

20 The objects of the invention are to provide wagons of this class having improved frame parts, and improved means for connecting the wheels with the frame and body.

25 With these and other objects in view, the invention consists in the construction and arrangement of parts which I have shown in the accompanying drawings. I desire 30 it to be understood, however, that many changes may be made in the construction without departing from the spirit of my invention.

Of the drawings—Figure 1 is a side elevation, Fig. 2 is a plan view, and Fig. 3 is an end elevation.

35 Referring to the drawings, 1 represents as a whole the body supporting frame. This frame is rectangular and comprises four beams of structural steel connected at their corners by angle-plates 2, 2. The beams may be either I-beams or channels, but in the drawings I have shown the short end beams 3, 3 as I-beams, and the long side 40 beams 4, 4 as channels. Immediately beneath each end frame beam 3 are two structural steel sections 5 and 6, preferably I-beams. These sections are somewhat shorter than the beams 3, and are bolted or riveted 45 to each other and to the end beam in such a way that the webs of all three sections are in vertical alinement.

50 7, 7 represent angle bars connected transversely between the two side beams 4, 4. These angle bars are adapted to partly support the wagon body as will be hereafter explained. Between each pair of angle bars 7, there are connected strap bars 8, 8, which

at their lower ends are connected to the bottoms of the structural sections 6.

55 9, 9 are castings bolted to the bottoms of the sections 6. These castings are partly circular in form, and are provided at their bottoms with horizontal smooth bearing surfaces.

60 10, 10 are castings similar to the castings 9, and are provided with oppositely formed bearing surfaces adapted to engage with the bearing surfaces of the castings 9. King bolts 11, 11 pass vertically through suitable 65 apertures located centrally in the castings 9 and 10 and serve as pivots about which the castings 9 and 10 may rotate relative to each other.

70 12, 12 are the main axles and are connected to the castings 10, 10 by means of caps 12^a, 12^a secured by bolts 13, 13. I prefer to make the axles round, but any other desired shape may be used. The main supporting wheels 14, 14 are rotatably secured 75 at the ends of the axles. These wheels are provided with broad tires which permit the use of the wagon on soft roads without injury to the road, and without excessive loss of power.

80 15 represents the wagon body as a whole. This body is mounted within and supported by the structural steel frame work 1. The body comprises the parallel sides 16, 16, which are flared outwardly near their upper ends at 17, 17, and the sloping end walls 18, 18. The bottom of the wagon is made up of swinging doors 19, 19. The framework of the wagon body consists of the three parallel transverse beams 20 at the 90 bottom, the two longitudinal beams 21 connecting the ends of the beams 20 and the eight longitudinal beams 22, which are located four at each end, and which support the inclined ends of the body. The beams 22 intermediate their ends rest upon and are connected with the transverse angle bars 7. The upper ends of the two inner beams at each end of the wagon are supported on the frame beams 3 by means of braces 23. 95 The sides of the wagon body are connected to the wagon frame by means of the brackets or braces 24 and 24^a. Reinforcing straps 25 are preferably provided along the inner surfaces of the sides 16.

100 26, 26 are braces or reaches adapted to

give longitudinal support to the bottom parts of the fifth wheels, which may be considered as comprising the castings 9 and 10. These braces 26 are connected at their inner ends to the wagon body and at their outer ends are provided with apertures through which pass the lower ends of the king bolts 11, 11. The braces are held in place by means of suitable devices such as 10 washers and cotter pins.

27, 27 represent diagonal braces connecting the central parts of the reaches 26, 26 with the sides of the bottom framework of the wagon body. These braces are riveted 15 to the straps 27^a, and in this way a direct metallic connection is made between the two axles. The straps 27^a have been shown in the drawings as connected with and reinforcing the body structure, but it will be understood that if desired, separate links corresponding in function to the straps 27^a may be used for connecting the inner ends of the braces 27. The purpose of the connecting system comprising the braces or reaches 20 26, the braces 27 and the straps 27^a is to provide a tension transmitting device which shall be as straight and direct as possible.

Near the outer ends of each of the axles 12 are provided clips 28, 28, each having 30 outer and inner eyes 29 and 30. The outer eyes 29 are adapted to have connected to them by suitable pins, links 31, 31. The forward ends of these links are connected to a traction engine, or to another wagon, and 35 therefore serve as draft links for drawing the wagon. The inner eyes 30, 30 of the clips 28, 28 are adapted to be connected with locking links 32, 32. These links are forked at their inner ends and are adapted to fit 40 over the braces 27, 27 and to be secured thereto by means of pins 33, 33.

As has been stated, wagons embodying my invention are adapted to be hauled by traction engines either singly or in trains. In 45 order that each wagon may have another wagon connected with it to be hauled, I provide an aperture in the outer end of each reach 26 as shown in Fig. 2. When two or more wagons are to be connected together, 50 the draft links 31, 31 of one wagon are connected by means of a suitable pin to the reach 26 of the next wagon.

34, 34 are two shafts extending transversely of the wagon and mounted in suitable bearings on the under side of the beams 4, 4. At one end of each shaft is a ratchet wheel 35, and a pawl 36 is provided to engage with each ratchet wheel. The outer ends of the shafts 34 are squared and are 55 adapted for engagement by a crank such as indicated by 37. Chains 38, 38 are connected to the shafts 34, 34 near their outer ends and are adapted to be wound upon the shafts. The lower ends of the chains 38 are 60 connected to horizontal levers 39, 39 at the

ends of which are connected other chains 40. The lower ends of the chains 40 are connected to the doors 19, 19 by means of suitable devices such as staples 41, 41 and T-bars 42, 42.

It will be noted that when the wagon is 70 filled with material and one of the pawls 36 is released, the weight of the doors will cause them to open, the chain 38 being unwound from the shaft 34. When it is desired to close the doors, the crank 37 is connected to the end of the shaft, and the shaft is turned to wind the chain 38. The link 39 serves to equalize the force which is transmitted to the two doors, and the result 75 is that the doors are normally closed simultaneously. However, if a piece of rock or other substance should become so lodged as to prevent the complete closing of one of the doors, the link 39 will tip and permit the 80 complete closing of the other door.

It will be noted that by means of the construction which has been set forth for connecting the wheels with the body and the frame, this wagon is adapted to be drawn in 85 either direction. The links 31, 31 may be connected at either end and the links 32, 32 may be secured in place at the end opposite to the links 31, 31. In this way it is always 90 possible to secure whichever pair of wheels 95 is in the rear in alinement with the direction of motion.

It will be observed that the framework of the wagon is largely independent of the body and that the framework is adapted to 100 take the greater part of the stresses due to the load. Even the load on the doors 19 is transmitted through the chains directly to the framework. The stresses due to the movement of the wagon are taken almost entirely by the reaches 26, 26, the diagonal braces 27, 27 and the connecting straps 27^a, 27^a. It will therefore be seen that the body 105 itself is free from all unnecessary stresses.

In a co-pending application, Serial No. 110 552,685, filed Mar. 31, 1910, of which this application is a division, I have shown and claimed the specific draft connections which are herein disclosed.

What I claim is:—

1. In a wagon, the combination of a frame comprising two side beams of structural metal sections, two end beams of structural metal sections and a plurality of supplementary structural metal sections secured parallel to and beneath each of the end beams with their webs in vertical alinement with the web of the end beam, supporting wheels connected with the lower of the supplementary metal sections, and a body located within and suspended from the frame, substantially as set forth.

2. In a wagon, the combination of a frame comprising two side beams of structural metal sections, two end beams of structural metal sections, and a body located within and suspended from the frame, substantially as set forth.

metal sections and a plurality of supplementary structural metal sections secured parallel to and beneath each of the end beams with their webs in vertical alinement 5 with the web of the end beam, supporting wheels, connections between the supporting wheels and the lower of the supplementary metal sections, one of said connections comprising a fifth wheel, a body located within

and suspended from the said frame, and 10 connecting devices between the body and the wheels, substantially as set forth.

In testimony whereof I affix my signature, in presence of two witnesses.

JOHN B. BARTHOLOMEW.
